Patented Nov. 29, 1910.

UNITED STATES' PATENT OFFICE.

FREDERIC W. C. SCHNIEWIND, OF NEW YORK, N. Y.

APPARATUS FOR CLEANING GAS-PIPES.

976,933.

Specification of Letters Patent. Patented Nov. 29, 1910.

Application filed October 24, 1907, Serial No. 398,899. Renewed April 23, 1910. Serial No. 557,265.

To all whom it may concern:

Be it known that I, FREDERIC W. C. SCHNIEWIND, a citizen of the United States of America, residing in the city, county, and State of New York, have invented a certain new and useful Improvement in Apparatus for Cleaning Gas-Pipes, of which the following is a true and exact description, reference being had to the accompanying drawings, which form a part thereof.

The object of the present invention is to provide simple and effective and effectively disposed means for cleaning out pipes or conduits, and particularly the conduits or pipes through which are passed the volatile products produced by the distillation of coal.

The purpose for which the apparatus disclosed was particularly designed is the cleaning out of the vertical stand pipes and lateral communicating escape vents and connecting pipes for the volatile products of coke ovens.

The various features of novelty which characterize my invention are pointed out with particularity in the claims annexed to and forming a part of this specification. For a better understanding of my invention, however, and the advantages possessed by it, reference may be had to the accompanying drawings and descriptive matter in which I have illustrated and described one of the forms in which my invention may be embodied.

Of the drawings, Figure 1 is an elevation, partly in section, of a portion of a large capacity coke oven structure equipped with the improved pipe cleaning mechanism. Fig. 2 is a diagrammatic plan showing the arrangement of the various escape and connecting pipes of one complete coke oven structure and the cleaning mechanism therefor. Fig. 3 is a sectional elevation showing the construction and arrangement of one of the cleaning devices and its supporting and driving connections.

In the drawings, A represents the fire-brick walls of the ovens proper, A' the masonry supporting shell surrounding the masonry A, and A² the removable top wall of one of the retorts A⁶. At each end of each retort are formed a plurality of inclined escape vents or passages for the volatile products of the coking operation. The upper one of these vents leads from the extreme upper end of the retort and the others from lower levels. Clogging of the lower

ends of the two lower vents at each end of the retort is prevented by the forebays A⁵.

At the outer ends of the vents A³ are provided stuffing boxes B into which extend pipes B', which are connected at their upper ends by ball and socket joints B² to the vertical stand pipe B³ for that end of the retort, there being one of these stand pipes at each end of each retort. The lower end 65 of the stand pipe B³ dips into a receptacle B⁴ into which the portion of the volatile products which condenses in the stand pipe may flow. The lateral extension of each main pipe B³ is preferably sloped as indicated at B⁶ so that the condensed material will not tend to obstruct the lateral connection.

The upper end of each stand pipe is supported by a portion D³ of the metal structure D at the side of the masonry. The upper end of each stand pipe B³, in the form shown, is connected to a connection C, and the connections C are in turn connected to a pair of parallel mains C' and C². Valves C³ provide for the connection of the upper end of each stand pipe to one or the other of the mains C' and C² as may be desired. It will be understood that the main C' and C² may be one a "rich" gas main and the other a "poor" gas main, and the valves of each connection are operated accordingly as the gas passing into the connection from the pipe B³ is "rich" or "poor."

Above the connections C the structure D supports a pair of parallel lower track rails D' running at the side of the battery and an upper rail D² running above the inner rail D'. A carriage E, having its wheels E' running in contact with the rails D' and D² 95 as shown in Fig. 1, supports the cleaning mechanism proper. This mechanism includes a vertically moving cleaner E⁹ and three cleaners H are supported to move in a direction parallel to the vents A³ and pipes B'. 100

The cleaners H are supported in a frame comprising vertical members F and F³, inclined tubular members F⁴, horizontal members F⁵, and bearing members F' and F². The frame is supported by the bearing members F' and F² which are mounted on the extension E¹⁴ of the main platform of carriage E and a lower platform E¹⁵ supported by the brackets or ties E¹⁶. The connection between the tubular members F⁴ and the vertical frame member F is formed by gear casings G, each of which has journaled in

it a spiral gear K. The gear K has keyed to it a hollow sleeve H' provided at one end with a bushing H² through which passes the operating shaft H³ of the corresponding cleaner H. The shaft H³ and the bushing H² are non-rotatingly but slidingly connected. For instance, the shaft H³ may be square or hexagonal in cross section and the hole in the bushing H² through which the shaft is 5 freely movable longitudinally of the same shape. To the upper end of each shaft H³ a swivel connection H⁶ is attached. A cord or other flexible connection F¹⁰ runs from each swivel H⁶ over pulleys F¹¹ secured to frame member F³ and a pulley F¹² secured to the frame at the upper end of the frame member F. From the pulley F¹² the cords pass to a winding drum F⁹ journaled in the main frame member F and rotated through 10 suitable intermediate gearing by a worm F⁸ carried by the shaft F⁷ of a vertical electric motor mounted on the bearing member F'. The shaft F⁷ passes through gear case extensions G' of the gear case G, and within 15 each of said extensions carries a worm gear (not shown) meshing with the corresponding gear K, so that the motor F⁶ rotates the cleaners H and also moves them in the direction in which their shafts H³ extend. The 20 carriage E also supports a motor E² which through a chain or other gear between its shaft and one of the axles of the carriage propels the latter along the track rails D' and D when necessary. It also supports a 25 motor E⁴, which is geared to the shaft E⁵ of the winding drum E⁶ for the cord or other flexible connection E¹⁰ connected to the upper end of the shaft E⁸ of the cleaner E⁹. The cord E¹⁰ runs over the pulley E¹¹ mounted 30 on the upper end of the tubular member E¹² which extends upward from the gear casing E⁷ and guides the shaft E⁸ of the vertically movable cleaner E⁹. Gearing located 35 in the casing E⁷ and driven by the motor E⁴ rotates the cleaner shaft E⁸. It will be understood that the connections for rotating and moving the shaft E⁸ longitudinally are similar to those for operating the inclined cleaner shafts H³. 40

In operation, when it is desired to clean the stand pipe B³, the carriage is moved in the proper position to bring the cleaner E⁹ over the pipe B³ to be cleaned, and the motor E⁴ is set in operation, the cover C⁵ being removed to permit the entrance of the cleaner E⁹ into the pipe B³. The motor E⁴ then rotates the cleaner E⁹, which may be in the form of a spiral cutter or other known 45 cleaning device, while at the same time through the winding drum E⁶ and cord E¹⁰ it controls the descent of the cleaner. When the cleaner has moved to the bottom of the stand pipe it may be brought back to the top by simply reversing the motor. Of course, it will be understood that suitable 50

60

65

clutching mechanism may be interposed if it is desired to withdraw the cleaner without rotation or while rotating in the direction in which it is rotated in descending. The material scraped off the inner wall of the pipe B³ of course drops to the receptacle B⁴. 70

The operation of the cleaning pipes B' and vents A³ is analogous to that of cleaning the pipes B³. The cleaners H are entered through the suitably placed openings in the stand pipe B³ which are normally closed by the covers B⁶, and the cleaners are then fed through the pipes B' and vents A³ to the inner ends of the latter. The solid matter scraped off the pipe and vent walls falls to the bottom of the coking retort. While the purpose of providing for the ball joints B² and stuffing boxes B' is to permit of a change of position of the vents A³ and the pipes B' relative to the stand pipe B³, 80 produced by contraction and expansion as the temperatures of the parts change, it will be understood that such movement is not great enough to materially affect the alinement of the pipes B' and the vents A³, 85 and shafts H³ are sufficiently flexible so that no difficulty in the operation of the cleaning device is experienced thereby. The rails D' and D² may extend all the way around the battery, as shown in Fig. 2, so that one 90 cleaning machine may be employed to clean all the vents and passages of the battery, or of course there may be a cleaning machine at each side of the battery. By preference, the members F' and F² are pivotally supported on the platforms E¹⁴ and E¹⁵ so that the frame of the inclined cleaners may swing around to the position shown in Fig. 2, to facilitate alteration, adjustment, or lubrication of the outer parts of the cleaner 95 mechanism. 100

With the arrangement shown, the cleaners H for the lateral pipes B' and vents A³, as well as the cleaners E⁹ for the main pipe B³, tend to move down under the action of gravity, and this of course may be supplemented by the rotary action of the cleaners when they are of the screw type. The cords, therefore, merely regulate the descent of the cleaners though serving to positively withdraw them on the return movement. It will be observed that with the flexible means controlling the advancing movement of the cleaners that if any one cleaner is temporarily checked in its forward movement as 110 by a local excessive accumulation of material in the pipe cleaned by it, such checking will not interfere with the operation of the other cleaners. 115

No claim on the general construction of 125 the retort or of the top door or wall thereof is made herein, as such features are claimed in my co-pending applications Nos. 398,902 and 398,904, respectively, filed of even date herewith. 130

Having now described my invention, what I claim as new and desire to secure by Letters Patent is:

1. A machine for cleaning a main pipe and lateral connections thereto, said machine comprising a supporting structure, bearings carried by said structure, a main pipe cleaner and lateral pipe cleaners, shafts carrying said cleaners and mounted in said bearings and axially movable therein, the lateral pipe cleaner carrying shafts extending at an angle to the main pipe cleaner carrying shaft, and mechanism supported on said structure for rotating said shafts and controlling their axial movement. 70
2. A machine for cleaning a main pipe and lateral connections thereto, said machine comprising a supporting structure, bearings carried by said structure, a main pipe cleaner and lateral pipe cleaners, shafts carrying said cleaners and mounted in said bearings and axially movable therein, the lateral pipe cleaner carrying shafts extending at an angle to the main pipe cleaner carrying shaft, mechanism supported on said structure for rotating said shafts and controlling their axial movement, and means for moving the lateral pipe cleaner shafts bodily about an axis parallel to the main pipe cleaner shaft. 80
3. In a pipe cleaning machine, a frame comprising a plurality of tubular members, a pipe cleaner shaft extending into and projecting from each of said tubular members, means for rotating said shafts while permitting them to move axially in said tubular members, and means for controlling the axial movement of said shafts in said tubular members. 90
4. In a pipe cleaning machine, a frame comprising a plurality of tubular members, a pipe cleaner shaft extending into and projecting from each of said tubular members, means for rotating said shafts while permitting them to move axially in said tubular members, and means for controlling the axial movement of said shafts in said tubular members, said means including a flexible connection for each shaft, each connection entering the corresponding tubular member at one of its ends and being connected to its shaft within said tubular member, and winding mechanism to which all of said flexible connections are connected. 100
5. In a pipe cleaning machine, a supporting frame, a plurality of pipe cleaning shafts journaled in said frame, mechanism for rotating said shafts and for regulating their movement in the direction of their lengths, said mechanism including a single motor on said frame and operating connections from it to each shaft for rotating the latter and for controlling its longitudinal movement. 110
6. In a pipe cleaning machine, a carriage, a frame supported thereby, a plurality of pipe cleaning shafts journaled in said frame, mechanism for rotating said shafts and for causing them to move in the direction of their lengths, and means for moving said frame bodily with respect to said carriage. 120
7. A coke oven construction provided with parallel inclined passages leading from each coking chamber, and stand pipes into which the connections from the retort enter, in combination with a carriage provided with a vertically movable cleaner for cleaning the stand pipes and inclined cleaners for cleaning the inclined passages, and operating connections for the cleaners. 125
8. In combination with a coke oven structure having a plurality of stand pipes and a plurality of branch pipes connecting each stand pipe to the interior of the coke oven structure, each stand pipe having removable covers, one in line with and on the opposite side of the stand pipe from each of said branches, a carriage, a track supporting the latter and permitting it to be moved into the positions to operate on the branches from the various stand pipes, a plurality of cleaner shafts, one for and adapted to be brought into alignment with each of the branch pipes of a single stand pipe, bearings for said shafts supported by said carriage, and means for rotating said shafts and means for giving them a regulated movement in the direction of their lengths to cause them to enter the branch pipes through said openings in the main pipe. 130
9. In combination with a coke oven structure having a plurality of stand pipes at one side and a plurality of connections from each stand pipe to the interior of the coke oven structure, each stand pipe having a removable cover, one in line with, and on the opposite side of the stand pipe from, each of said branches, a carriage, a track supporting the latter and permitting it to be moved into the positions to operate on the branches from the various stand pipes, a plurality of cleaner shafts, one for and adapted to be brought into alignment with each of the branch pipes of a single stand pipe, bearings for said shafts supported by said carriage, means for rotating said shafts, means for giving them a regulated movement in the direction of their lengths to cause them to properly enter the branch pipes through said openings in the main pipe, each stand pipe having a removable top cover, and a vertically movable and rotatable cleaner shaft supported by said carriage and movable into each stand pipe through its upper end when the top cover is removed. 140
10. In a pipe cleaning machine, a frame comprising a pair of side members and a plurality of tubular cross members connecting said side members, cleaner shafts, one projecting from each tubular member, a

- driving shaft, and gearing connecting the driving shaft with the various cleaner shafts adjacent the ends of the corresponding tubular members.
- 5 11. In a pipe cleaning machine, a frame comprising a pair of side members and tubular cross members connecting the side members, the connection between one of the side members and the tubular members being formed by gear cases, a driving shaft extending through said gear cases, cleaner shafts, one extending through each gear case into the corresponding tubular member, and gearing in each gear case for connecting the driving shaft and the corresponding cleaner shaft.
- 10 12. In a pipe cleaning machine, a frame comprising a pair of side members and tubular cross members connecting the side members, the connection between one of the side members and the tubular members being formed by gear cases, a driving shaft extending through said gear cases, cleaner shafts extending through the gear cases into the corresponding tubular members, gearing in each gear case for connecting the driving shaft and the corresponding cleaner shaft, and a motor supported by the frame for rotating said driving shaft, a winding mechanism also driven by said motor and supported by said frame, and a flexible connection running from said winding mechanism to each cleaner shaft, each flexible connection entering the tubular member guiding the corresponding cleaner shaft at the end of the member remote from that connected to gear casing, and a carriage to which said frame is connected and from which said frame normally extends at an angle, the connecting means between the frame and the carriage permitting the former to be swung around to the side of the carriage.
- 15 13. In a pipe cleaning machine, a frame comprising a pair of side members and tubular cross members connecting the side members, the connection between one of the side members and the tubular members being formed by gear cases, a driving shaft extending through said gear cases, cleaner shafts extending through the gear cases into the corresponding tubular member, gearing in each gear case for connecting the driving shaft and the corresponding cleaner shaft, a motor supported by the frame for rotating said driving shaft, a winding mechanism also driven by said motor and supported by said frame, a flexible connection running from said winding mechanism to each cleaner shaft, each flexible connection entering the tubular member guiding the corresponding cleaner shaft at the end of the member remote from that connected to gear casing, and a carriage to which said frame is connected and from which said frame normally extends at an angle, the connecting means between the frame and the carriage permitting the former to be swung around to the side of the carriage.
- 20
- 25
- 30

the corresponding cleaner shaft at the end 35 of the member remote from that connected to the gear casing.
